UNITED STATES PATENT OFFICE

FRITZ HOFMANN, OF BRESLAU, GERMANY, ASSIGNOR TO I. G. FARBENINDUSTRIE AKTIENGESELLSCHAFT, OF FRANKFORT-ON-THE-MAIN, GERMANY, A CORPORATION OF GERMANY

OXIDIZING PARAFFINS, WAXES, AND THE LIKE

No Drawing. Application filed March 14, 1928, Serial No. 261,708, and in Germany March 18, 1927.

This invention relates to the production of valuable organic compounds by oxidizing paraffins, waxes and the like.

In carrying out the oxidation of paraffin hydrocarbons, waxes and the like by means of a gas containing oxygen such as air, it is already known to employ inorganic catalysts, such as metals, metallic oxides or salts, including metal salts of organic acids.

10 I have now found that this reaction may be considerably accelerated by employing the said catalysts associated with organic nitrogenous bases. As examples of such nitrogenous bases may be mentioned aniline, 15 pyridine, quinoline, butylamine, toluidine and cyclohexylamine.

The following example will further illustrate the nature of the said invention and the surprising result thereby obtained, but 20 the invention is not limited to this example.

Example

When paraffin wax alone is oxidized with air at 170° C., it gives the saponification values 88.8 and 147.4 after being treated for 2 and 4 hours respectively. If 1 per cent of manganese soap be added before the oxidation, the corresponding values are 97.2 and 169.5; whilst if the 1 per cent of manganese 30 soap be added associated with 0.1 per cent of hexamethylenetetramine, the saponification value after 2 hours amounts to 135.3; after 4 hours to 217, and after 6 hours to 271.2.

35 Instead of hexamethylenetetramine and manganese soap, use may also be made of other organic bases, such as amines, or of other catalysts such as cerium oxid or its salts, for example cerium stearate.

40 What I claim is:

1. A process for the oxidation of paraffin hydrocarbons, which comprises oxidizing the said hydrocarbons by means of a gas 45 containing oxygen in the presence of an inorganic catalyst associated with organic nitrogenous bases.

2. A process for the oxidation of paraffin hydrocarbons, which comprises oxidizing 50 the said hydrocarbons by means of air in the

presence of an inorganic catalyst associated with organic nitrogenous bases.

3. A process for the oxidation of paraffin hydrocarbons, which comprises oxidizing paraffin wax by means of air in the presence 55 of manganese soap associated with hexamethylenetetramine.

In testimony whereof I have hereunto set my hand.
